Baldwin & Wright*

UNITED STATES PATENT OFFICE.

EARL M. TRAMMELL, OF EL PASO, TEXAS, ASSIGNOR TO EL PASO SASH & DOOR COMPANY, OF EL PASO, TEXAS.

BUILT-IN WALL SEAT.

Application filed October 28, 1927. Serial No. 223,344.

This invention relates primarily to a wall seat adapted to be built-in to the wall of a room and opened into operative position whenever desired. Although illustrated in connection with a wall seat, it is obvious that the same mechanism may be applied to a small table, ironing board or the like and the invention is, therefore, not to be regarded as limited except by the scope of the claims.

10 In the drawings:

Figure 1 is a perspective view of the wall seat shown in open position.

Figure 2 is a front view with the seat in closed position.

15 Figure 3 is a vertical section on the line 3—3 of Figure 2.

Figure 4 is a horizontal section on the line 4—4 of Figure 3 showing one-half of the device.

20 The device is adapted to set into a suitable opening in any wall A either when the building is constructed or thereafter. It comprises a box like member having a top 1, bottom 2, back 3, and side walls 4. An ornamental front is provided with side panels 5, a top panel 6, and a lower panel 7. These front panels may be of any desired configuration or design to conform to the appearance of the remaining woodwork of the room.

30 Hinged at 8 to the upper edge of the bottom panel 7 is a board 9 which has hinged to the other end thereof at 10 a short member 11 provided with a handle or knob 12 and having in its edge a spring pressed ball detent 13 adapted to cooperate with a seat 14 in the edge of the top panel 6 to hold the parts in closed position.

A seat 15 has its front ends fastened to the inner face of the member 11 in any desired 40 manner as by wooden pins and has at its rear end a rod 16 attached to the upper surface thereof, which rod is preferably of wood and is fastened to the seat 15 by bolts or other suitable fastenings. The ends of this rod 45 project beyond the sides of the seat 15 into grooves 17 in the side members 4.

Hinged to the upper surface of the seat 15 at a point spaced a slight distance from the rod 16 is a board or panel member 19 attached 50 to the seat 15 by hinges 18. This member 19 has at its free end and on the rear or under surface thereof, a wooden rod 20, the ends of which project beyond the sides of the board and are guided in grooves 21 in the side members 4.

The grooves 17 are irregular in form and are designed to produce the desired movement of the seat member 15 to and from open position. These grooves terminate in a short forward extension 22 at the upper ends thereof into which the ends of the rods 16 fit when the seat is in its fully open position. As will be noted, the edge of the member 19 which is adjacent the seat 15 is cut at such an angle that when the parts are in fully open position, it will contact fully with the upper face of the seat 15.

55 The operation of the device is believed to be apparent from the above description. Assuming that the parts are in closed position and it is desired to open the same, a forward pull on the knob or handle 12 will cause the rod 16 to start its upward movement in the groove 17 which will result in the forward movement of the seat 15 and the supporting members 9 and 11, such movement being permitted by the hinges 8 and 10. At an intermediate position the parts occupy the position shown in Figure 3 in dotted lines and it is to be noted that in this opening movement, the rod 20 is travelling upward in the grooves 21, this being permitted by the hinges 18.

60 When the parts are in the fully open position shown in Figures 1 and 3, the ends of the rods 16 rest in the end portions 22 of the grooves 19. The rear end of the seat cannot move directly upward, directly forward, nor directly downward. Since it cannot move forward, no further movement about either of the hinges 8 or 10 is permissible and the member 9 therefore acts as a brace. At the same time, the upper end of the member 19 has reached a position where the face thereof substantially contacts with the inner side of the lower edge of the front 65 panel 6 while the rod 20 prevents the same from moving directly toward the rear. The end of the member 19 also substantially contacts with the under side of the top member 1.

70 It will be obvious that the seat is held firmly in position and can sustain any desired amount of weight on any portion thereof. Nevertheless when it is desired to return the parts to closed position, a slight rearward push on the front end of the seat member, followed by a lifting movement, will cause the parts to move back rapidly into closed position.

75 80 85 90 95 100 105 110 It is obvious that the size and dimensions of the various parts may be changed as de-

110

sired for various purposes. Various details of the construction may be modified and it is to be understood that the invention is limited only by the scope of the appended claims.

5 I claim as my invention:

1. A built-in wall seat or the like, comprising an open front receptacle having upper and lower grooves in one of its sides, a seat provided with a guide pin working in the lower groove, a lower brace hinged at its lower end to the front of the receptacle and at its upper end to said seat, and an upper brace hinged at its lower end to the seat and carrying at its upper end a guide pin working in the upper groove,
- 10 10 in the upper groove, the upper end of the upper brace being maintained within the receptacle at all positions of the seat.
- 15

2. A built-in wall seat or the like, comprising an open front receptacle having upper and lower grooves in one of its sides, the upper groove extending downwardly and rearwardly and the lower groove extending downwardly and forwardly, a seat provided with a guide pin working in the lower groove, a lower brace hinged at its lower end to the front of the receptacle and at its upper end to said seat, and an upper brace hinged at its lower end to the seat and carrying at its upper end a guide pin working in the upper groove.

30 In testimony whereof, I have hereunto subscribed my name.

EARL M. TRAMMELL.
